[57] CLAIM

The ornamental design of a telephone base, as shown and described.

DESCRIPTION

FIG. 1 is a top, front and left side perspective view of a telephone base showing our new design;

FIG. 2 is a top plan view thereof;

FIG. 3 is a bottom plan view thereof;

FIG. 4 is a front elevation thereof;

FIG. 5 is a rear elevation thereof;

FIG. 6 is a left side elevation thereof; and,

FIG. 7 is a right side elevation thereof.

The broken line showings in FIGS. 1, 2, and 4 are intended to represent contour shading.
